CARL G. WAGNER AND JOHN M. KERR, OF BAY CITY, MICHIGAN, ASSIGNORS TO BAY CITY DREDGE WORKS, A CORPORATION OF MICHIGAN.

CROWDING MECHANISM.

Application filed April 15, 1926. Serial No. 102,132.

This invention relates to excavating machines and more particularly to the dipper stick crowding mechanism thereof.

One object of the invention is to design a crowding mechanism which will permit the dipper to be crowded into the work at the same time as it is being hoisted.

Another object of the invention is to design a dipper stick crowding mechanism of very simple construction which will positively and quickly force the dipper into the work.

A further object is to provide a substantial and cheap crowding mechanism of simple construction, which is very easy to assemble and operate.

A further object still is to design a cable crowding mechanism particularly adaptable for excavators on which the main frame or carriage is non-revolving.

With the above and other objects in view, the present invention consists in the combination and arrangement of parts, herein-after more fully described, illustrated in the accompanying drawings and particularly pointed out in the appended claims, it being understood that changes may be made in the form, size, proportion and minor details of construction, without departing from the spirit, or sacrificing any of the advantages of the invention.

In the drawings—

Fig. 1 is a side elevation of a boom and excavating shovel illustrating our improved crowding mechanism in position.

Fig. 2 is an enlarged fragmentary side view of the boom and crowding mechanism.

Fig. 3 is a top plan view thereof.

Fig. 4 is a transverse sectional view taken on the line 4—4 of Fig. 3.

Referring now particularly to the drawings in which we have shown the preferred embodiment of our invention, the numeral 5 indicates the boom which can be of any suitable construction, and which is held in any desired position of inclination by means of a cable 6 secured to a mast 7 in the usual manner. The inner end of the boom is pivotally secured to the excavating machine (not shown) at the point 8, and is swung by means of a suitable turntable or circle 9 provided on the machine. Spaced apart fabricated members 10 comprise the boom proper, and a double stick dipper handle 11 is

mounted for travel therebetween, a conventional dipper 12 being secured to the lower end thereof in the usual manner, and toothed racks 13 are secured to one side of each stick as shown, an angle 14 being fixed to the stick adjacent the upper end of the rack and forms a stop to limit the downward travel of the dipper handle.

The crowding mechanism is mounted on the boom 5 and comprises a transversely disposed shaft 15 journaled in suitable bearings 16 mounted on the boom members. A reduction drum "A" is loosely mounted on this shaft 15 and is formed as clearly shown in Fig. 4 of the drawings, the drum 17 being of larger diameter than the drum 18 and preferably formed integral therewith, the end of the drum 17 being dished as shown at 19 and forming one part of a friction clutch, the surface of said clutch being preferably suitably lined to secure proper frictional contact. A second auxiliary reverse crowding drum "B" is keyed on the shaft 15 directly adjacent the reduction drum, the end 20 forming the male half of the friction clutch, and a cable 21 is anchored to and wound on said drum (not shown) and which is mounted on the excavator frame.

A spur pinion 22 is mounted on one end of the shaft 15, said pinion meshing with a gear 23 which is secured on a transversely disposed shaft 24 directly adjacent the shaft 15, and which is journaled in suitable bearings 25 mounted on the boom.

Spaced apart spur pinions 26 and 26^a are mounted on the shipper shaft 24 and saddles 27 and 27^a embrace the pinions and loosely engage the shaft, the sticks 11 which form the dipper handle, extending therethrough, and the racks engage the pinions, so that, when the pinions are rotated, the dipper stick will be raised or lowered accordingly.

A hoist cable 28 is anchored to and wound on the drum 18, thence leading to and being secured to the dipper 29, a second cable 30 being anchored to and wound on the drum 17, thence leading to the hoist drum (not shown) on the machine, and it will be obvious that as the hoisting drum is rotated, the reduction drum will be actuated, the cable 28 will be wound on the drum 18, and the dipper raised accordingly, a brake (not shown) being provided on the hoisting drum on the machine for holding the dipper in

any position, release of the hoist drum allows the dipper to drop by gravity, preparatory to being forced into the work.

Eccentric clutch levers 31 and 31^a are loosely mounted on the shipper shaft, the lever 31 being secured to a bracket 32 which is bolted to the boom frame, said bracket being provided with spaced apart openings therein so that the lever may be set as desired, a reach rod 33 is connected to the end of the opposite lever 31^a, and is pivotally connected to a foot pedal on the machine, a collar 34 being interposed between the bearings and the eccentric clutch lever, and when it is desired to shift the friction clutch into engagement, the foot lever is actuated, which in turn actuates the clutch lever 31^a, thereby shifting the reduction drum transversely on the shaft, and the friction clutch into engagement, this drives the gears to shift the dipper into the work simultaneously as the cable is wound on the drum 18 to hoist the bucket, release being effected by releasing the foot lever, and the coiled spring 35, which is interposed between the drums "A" and "B".

The relative diameters of the drums 17 and 18 provide a substantial reduction, and this ratio can be increased or reduced as desired.

In the construction shown when the hoist drum is released the dipper is lowered by gravity to the desired digging position, from where it may be hoisted and crowded as above described. For bringing the dipper back to load close to front of machine, the momentum or swing established in lowering the bucket is utilized, also the rotation of the reverse crowding drum "B", caused by winding cable 21 on separate drum (not shown), on machine, is used to raise the dipper to clear the ground in the backward swing, and when bucket has reached limit of its backward swing it is dropped to the work, further, it is oftentimes necessary to shift the position of the dipper when loaded, as when dumping into vehicles of various kinds, and this can be quickly done with the reverse crowding drum as above described.

A suitable trip is provided on the bucket for dumping the load when in proper position, a trip line 36 leading up and to the operator on the machine.

From the foregoing description it will be obvious that we have perfected a substantial and effective dipper crowding mechanism, by means of which the dipper can be crowded into the work simultaneously with the hoisting thereof.

What we claim is:—

1. The combination with a boom, of a transversely disposed shaft journaled thereon, a reduction drum, an auxiliary drum adjacent thereto, the ends of said drum be-

ing shaped to form a friction clutch, a shipper shaft spaced from the transversely disposed shaft and geared thereto, a dipper handle, and pinions on said shipper shaft adapted to engage said dipper handle. 70

2. The combination with a boom, of a transversely disposed shaft journaled thereon, a reduction drum mounted on said shaft, an auxiliary drum adjacent thereto, the ends of said drums being shaped to form a clutch, 75 a shipper shaft spaced from the transversely disposed shaft and geared thereto, a dipper handle, gears on the said shipper shaft adapted to engage said dipper handle, and means on the transversely disposed shaft for shifting said drums into driving engagement with each other. 80

3. The combination with a boom, a transversely disposed shaft journaled thereon, a reduction drum mounted on the shaft, an auxiliary drum adjacent thereto, the ends of said drum being shaped to form a clutch, 85 a shipper shaft spaced from the transversely disposed shaft and driven therefrom, a double stick dipper handle, racks secured thereto, gears mounted on the shipper shaft and meshing with said racks, and saddles mounted on the shipper shaft and embracing said sticks to hold them in proper position. 90

4. The combination with a boom, a transversely disposed shaft journaled thereon, a reduction drum loosely mounted on the shaft, an auxiliary drum adjacent thereto, the ends of said drums being shaped to form a clutch, a shipper shaft journaled on 100 the boom adjacent the transversely disposed shaft, gears connecting said shafts, a double stick dipper handle, racks secured thereto, pinions on the shipper shaft and meshing with said racks, saddles mounted on the shipper shaft and embracing the dipper handle, and means for shifting said reduction drum into frictional engagement with the auxiliary drum. 105

5. The combination with a boom, a transversely disposed shaft journaled thereon, a reduction drum rotatably mounted on the shaft, an auxiliary drum adjacent thereto, one end of each drum being shaped to form a friction clutch, a shipper shaft journaled on the boom and spaced from the transversely disposed shaft, gears connecting said shafts, a dipper stick, racks secured thereto, pinions on the shipper shaft and engaging said racks, saddles pivotally mounted on the shipper shaft and embracing the sticks, and means for shifting the drum into frictional engagement for simultaneously driving the reduction drum and actuating said dipper sticks. 115

6. The combination with a boom, a transversely disposed shaft journaled thereon, a reduction drum rotatably mounted on said shaft, an auxiliary drum adjacent thereto, the ends of said drum being shaped to form 130

a friction clutch, a shipper shaft mounted on the boom and spaced from the transversely disposed shaft, gears connecting said shaft, a double stick dipper handle, racks secured thereto, pinions on the shipper shaft and engaging said racks, and saddles pivotally mounted on the shipper shaft and em-

bracing said sticks, means for forcing the drums into engagement to form a clutch and resilient means for releasing said clutch. ¹⁰

In testimony whereof we affix our signatures.
